WILLIAM HEBDON, OF NEW YORK, N. Y.

Letters Patent No. 87,930, dated March 16, 1869.

IMPROVEMENT IN MACHINE FOR DAMPING, &c., CLOTH.

The Schedule referred to in these Letters Patent and making part of the same.

To all whom it may concern:

Be it known that I, WILLIAM HEBDON, of the city and State of New York, have invented and made a new and useful Improvement in Machinery for Dampening, Shrinking, or Water-Proofing, and Drying, or Refinishing Woollen Fabrics; and I do hereby declare the following to be a full, clear, and exact description of the said invention, reference being had to the annexed drawing, making part of this specification, wherein—

Figure 1 is a vertical longitudinal section of said machine complete, and

Figure 2 is a plan of the same.

Similar marks of reference denote the same parts.

In the manufacture of garments, it is usual, with tailors, to sponge the cloth, or else roll it up into a wet cloth, to either shrink the cloth, or else to remove the gloss that would cause it to show rain-spots; and frequently it is desired to introduce into the cloth substances that will render the fibre water-proof to a large extent, so that the goods do not absorb rain or moisture with rapidity.

The methods heretofore pursued for effecting the aforesaid objects, are slow, and difficult to perform with uniformity and reliability, and my apparatus is designed with a view to facilitating said operations, and rendering them more perfect.

In the drawing—

a is a vat, for containing warm or cold water, either alone, or mixed with such known or desired materials, that the woollen fabric shall thereby be rendered more or less water-proof.

b is an open movable box, or crate, made with a lid that can be opened, to allow the cloth to be introduced into said box, and laid in folds, as seen in fig. 1. This is done when the crate *b* has been lifted up out of the box *a*.

The end of the cloth projects from this crate *b*, and after the crate has been pressed down in the water, and slid under the lower edge of vertical press-board *c*, to hold the same down, or otherwise kept in place, the cloth is led around the saturating-bar *d*, under the saturating-bars *e*, and between the spring squeezing-rollers *f*, to the winding-frame *g*.

The saturating-bars, *d* and *e*, are covered with cloth, or similar material, and act to insure the penetration of the immersing-liquid into the cloth, as it is drawn out of the box, or crate *b*.

The rollers *f* squeeze off surplus moisture, and also insure a thorough saturation of the cloth throughout its texture.

The winding-frame *g* is provided with a crank-handle at one end; and I prefer to use a sheet of galvanized iron upon which to wind the cloth.

By the mechanism before specified, a piece of cloth can be saturated so as to shrink it; or, by the use of proper substances in the liquid, said cloth may be water-proofed; or a piece of cloth can be damped, by winding it up inside the piece of cloth that is being drawn out of the vat, and wound upon the winder *g*.

Under most circumstances, the cloth, as wound upon the winder *g*, will contain too much moisture. I therefore provide the platen *h* and screw *i*, and lift the frame and winder *g* out of its supports, *k*, and introduce it between the platen *h* and press-board *c*, slots, at *l*, being provided for the journals of this frame *g*, and when the surplus water is squeezed out of the roll of cloth, the water runs back into the vat *a*.

The reel is afterwards replaced in the supports *k*, and the cloth unwound and inspected while passing over the roller *m*, the object of this being to discover whether there are any imperfections in the cloth.

The cloth passes down into a receptacle, *n*, below the receptacle *o* and pressing-table *p*. This may be connected, at this end of the apparatus, or be movable.

The operator, in pressing, or refinishing the cloth, passes the same successively along over the table *p*, and irons the same on the wrong side, or by the use of a suitable press-cloth, and, in so doing, he draws the cloth out of one receptacle, *n*, and passes it into the other receptacle, *o*, as refined. The dotted lines at these parts, in fig. 2, represent the manner in which the cloth is led.

This machine, being cheap, strong, and easily constructed and kept in repair, is adapted to general use among tailors, and cloth-finishing dealers.

The rollers *f* should be mounted in movable boxes, *g*, so that they can be easily lifted out of the way when it is desired to lift out the crate *b*, for introducing the cloth.

A movable table, or cover to the vat *a*, may be employed, as at *r*.

What I claim, and desire to secure by Letters Patent, is—

1. The crate *b* and saturating-bars, *d* and *e*, in combination with the squeezing-rollers *f* and winder *g*, substantially as and for the purposes set forth.

2. In combination with the foregoing, the press-board *c*, platen *h*, and screw *i*, applied within the vat *a*, and arranged, in relation to the winder *g* and rollers *f*, in the manner and for the purposes specified.

In witness whereof, I have hereunto set my signature, this 28th day of December, A. D. 1868.

W. HEBDON.
